Robert Burns

Atty.

UNITED STATES PATENT OFFICE.

CHARLES W. BEEHLER, OF ST. LOUIS, MISSOURI.

BOX-FASTENER.

SPECIFICATION forming part of Letters Patent No. 747,035, dated December 15, 1903.

Application filed September 19, 1903. Serial No. 173,813. (No model.)

To all whom it may concern:

Be it known that I, CHARLES W. BEEHLER, a citizen of the United States of America, and a resident of the city of St. Louis, in the State 5 of Missouri, have invented certain new and useful Improvements in Box-Fasteners, of which the following is a specification.

The present invention relates to that type of box-fasteners in which a turn-bolt having 10 a lateral extension at its upper end is attached to the box-body to constitute one member of the fastener and a bearing-plate is secured to the box-cover to constitute the other member of the fastening, the lateral end extension of 15 the turn-bolt being adapted to pass through an oblong opening in the cover-plate and by a turning movement to one side of said slot having bearing engagement upon the upper surface of the bearing-plate and held to such 20 engagement by an ordinary wire seal passing through said lateral extension and through a companion projection on the said plate.

The object of the present improvement is to provide a simple, strong, and efficient construction of the aforesaid bearing-plate involving cheapness and ease in manufacture combined with lightness and durability in continued use, all as will hereinafter more 25 fully appear and be more particularly pointed out in the claims.

In the accompanying drawings, illustrative of the present invention, Figure 1 is a top view of box-fastener embodying the present improvement and illustrating the adaptation of 30 the same to an ordinary wooden shipping-box. Fig. 2 is a longitudinal sectional elevation at line xx , Fig. 1. Fig. 3 is a transverse sectional elevation at line $x'x'$, Fig. 1.

Similar numerals of reference indicate like 40 parts in the different views.

Referring to the drawings, 1 represents the cylindrical body portion of the turn-bolt of the present fastener and which is secured to the box-body in a manner to permit a turning 45 of said body portion by means of a confining clip-plate 2, and a collar 3 on the lower end of said body portion engaging in a confining-recess 4 in said clip-plate to hold the turn-bolt against longitudinal movement, while 50 permitting the same to have free turning movement.

5 is a lateral extension on the upper end of

the turn-bolt body 1, and 6 is an orifice through said extension for the passage of the usual sealing-wire in sealing the contents of the box 55 before shipment.

7 is a bearing-plate secured to the box-cover and which in the present invention consists of a flat plate 1, of wrought metal, adapted for permanent attachment to the box-cover and formed with a central oblong hole or passage 8 of a size and shape to admit of the free passage of the aforesaid lateral extension 5 of the turn-bolt.

9 is an upwardly-projecting web on the 65 bearing-plate 7 near one end of the oblong slot 8 and extending the transverse width of such plate, as shown. In the present improvement such web is formed by upsetting the metal of the plate into a pair of right-angle folds connected together at top and having parallel relation to each other, as shown more particularly in Fig. 3.

10 represents a pair of orifices formed in the web 9 of the bearing-plate, and the arrangement is such that one or the other is adapted to register with the orifice 6 of the lateral extension aforesaid of the turn-bolt when the same is turned in one direction or the other toward the web 9 in a fastening operation of 70 the parts. Said orifices 10 so registering with the aforesaid orifice 6 are adapted to receive the wire loop of an ordinary lead seal generally used in the arts as a sealing means.

Having thus fully described my said invention, what I claim as new, and desire to secure by Letters Patent, is—

1. In a fastener of the character herein described, the combination of a turn-bolt, having a lateral extension at one end, and a bearing-plate adapted for engagement with said turn-bolt and provided with a central elongated passage and an upwardly-projecting web that extends the transverse width of the bearing-plate and is formed by upsetted folds 90 in the metal of such plate, substantially as set forth.

2. In a fastener of the character herein described, the combination of a turn-bolt, having a lateral extension at one end, and a bearing-plate adapted for engagement with said turn-bolt and provided with a central elongated passage and an upwardly-projecting web that extends the transverse width of the 95 100

bearing-plate and is formed by upsetted folds in the metal of such plate, the aforesaid lateral extension having a single orifice for a seal-wire, and the transverse web a pair of 5 orifices for such wire, arranged equidistantly from the center of such plate, substantially as set forth.

3. In a fastener of the character herein described, the combination of a turn-bolt, having 10 a lateral extension at one end, and a bearing-plate adapted for engagement with said turn-bolt and provided with a central elongated passage and an upwardly-projecting web that extends the transverse width of the

bearing-plate and is formed with a pair of 15 orifices arranged equidistantly from the center of said plate, the aforesaid lateral extension having a single orifice adapted to register with one or the other of the orifices in the web aforesaid to form a passage of a seal-wire, substantially as set forth. 20

Signed at St. Louis, Missouri, this 14th day of September, 1903.

CHARLES W. BEEHLER.
